UNITED STATES PATENT OFFICE.

ELIAS A. KAUFFMAN, OF CHICAGO, ILLINOIS.

AEROPLANE.

Application filed January 16, 1928. Serial No. 246,933.

This invention relates to aeroplanes, and more particularly to the type which include tubular blower mechanisms along with the customary propellers for actuating the aero-
5 plane.

The main object of this invention is to provide the aeroplane with tubular blower mechanism to be selectively controlled for either aiding the usual propellers in the forward 10 propulsion of the aeroplane, or to be rendered effective in buoying the aeroplane and to prevent any rapid or accidental dropping thereof. A further object is to provide tubular blower mechanism for forcefully withdraw-
15 ing the air from the front of the aeroplane body and selectively directing it either to the rear thereof to aid in the forward propulsion of the aeroplane, or to the bottom thereof for buoying the same. Another object is to have
20 an engine for operating the blower mechanism, which is independent from and separately controllable from the propeller engines. A further object is to provide control means placed in the pilot's cabin for control-
25 ling the engine means of the blower fans, and also for controlling the blower fan valve means to direct the forced air either to be expelled at the rear of the aeroplane or at the bottom thereof.
30 Other objects and advantages, along with those above referred to, are attained with this invention, as will become apparent from the following description, taken in connection with the accompanying drawings, in
35 which,

Fig. 1 is a plan view of the body and main parts of an aeroplane, a portion being broken away, with my invention applied thereto;

Fig. 2 is a vertical section, taken substantially through the longitudinal center thereof;

Fig. 3 is an enlarged vertical cross-section, taken on line 3—3 of Fig. 2; and

Fig. 4 is a vertical section, taken on line 45 4—4 of Fig. 3.

In the drawings my invention is illustrated in its preferred form of construction, and in conjunction with an aeroplane which has a flattened body 10 the top and bottom walls 50 of which converge to form horizontal front and rear edges 11 and 12, respectively. The main supporting plane 13 is mounted over the body, as with struts 14, and a pilot's cabin 15 is provided centrally over said body, beneath 55 said plane. A door 16 and steps 17 provide entrance to a central or entrance chamber

18 of the body, and steps 19 and a door 20 lead from said chamber to the pilot's cabin.

The propelling means of the aeroplane comprises tractor propellers 21 mounted forward of the front edge 11 of the body, on propeller shafts 22 which extend through bearing means 23 provided at said edge, and said shafts and propellers are actuated by engines 24 mounted in the front part of body 10, 60 forward of chamber 18.

My improved tubular blower mechanism preferably comprises an individual tubular blower means for each propeller and to operate in conjunction therewith; and each of said 65 tubular blower means includes a pair of connected intake tubes or branch tubes 26, each of which has a flaring intake mouth 27 positioned in the front edge 11 of body 10, preferably one at each side of and near to bearing 70 means 23 and shaft 22, and to the rear of propeller 21, so as to withdraw the air particularly from the front edge of the body and directly to the rear of the propellers, where the air becomes most congested and dense 75 during operation of the propellers and forward travel of the aeroplane. These branch tubes 26 have their junction 28 connected to a blower member or fan 29 which is provided with a branched or two-way outlet member 80 85 30 having a valve 31 therein for selectively controlling and directing the forced air either through the lower branch and ejecting it out of its flaring discharge mouth 32 located at the bottom of said body 10, or for directing 90 it through the rear tubular means 33 and out of the flaring discharge mouth 34 thereon at the rear of said body 10, and preferably just below the rear edge 12. The tubular means used at the middle of the aeroplane 95 preferably has its discharge means 33 branched so that a discharge mouth 34 is positioned at each side of the empennage 35, as indicated in Fig. 1; while the tubular blower means used toward the sides of the aeroplane preferably have one discharge tube 33' 100 and one discharge mouth 34' each.

The power supplying means for driving the blower members or fans 29 preferably comprises an engine 36 which may be mounted with bracket means 37 in chamber 18, and which actuates a shaft 38 extending transversely of the aeroplane and carrying pulleys 39 each of which drives a belt 40 extending around a pulley 41 fastened on a shaft 42 of 110 a blower fan.

Means is provided for controlling the en-

gine 36 and all the air directing means or valves 31 from the pilot's cabin 15, and this means preferably includes an electric starter 43 for this engine, being connected to the engine with conductor means 44 and being preferably mounted in the front of the pilot's cabin, to be readily accessible to the pilot. The valve actuating means preferably comprises a rod 45 extending transversely of the aeroplane and connected to the valves, and a link 46 which extends from a crank arm 47, provided on said rod, to a control lever 48 placed in the pilot's cabin.

It is apparent that this blower mechanism, by forcefully withdrawing the air directly from the front edge of the aeroplane where it is most congested and by forcefully ejecting it at the rear, will greatly aid the usual propellers in a more rapid forward propulsion of the aeroplane; and that this mechanism may likewise be employed to forcefully expel the air at the bottom of the aeroplane and thereby become effective in buoying the same and in preventing any sudden and dangerous dropping thereof. It is also apparent that the blower engine 36 is provided separately from the propeller engines 24 and the control means is placed in convenient reach of the pilot in the pilot's cabin, and therefore, that if the propeller engines or some of them should become inoperative, that this blower mechanism may be speedily used in saving the aeroplane from any rapid drop and destruction.

What I claim as my invention and desire to secure by Letters Patent is:

1. An aeroplane comprising a flattened body having a horizontal front edge and a propeller at the front thereof, tubular blower means in the body and having its air intake means at the front edge and behind the propeller, and means for actuating and for controlling said blower means independently from the propeller, or in co-operation therewith.

2. An aeroplane comprising a flattened body having its top and bottom walls converging into a horizontal front edge, a shaft mounted through said edge and having a propeller at the front thereof, and tubular

blower means having intake mouths placed in said edge adjacent said shaft and propeller for withdrawing the air from said front edge and forcefully discharging it rearwardly near the rear end of said body. 55

3. An aeroplane comprising a body and propellers thereon, tubular blower means including connected branches having their intake mouths at the front end of said body, a blower member at the junction of said branches, branched outlet means leading from said member, one branch having a discharge mouth at the rear part of the body, and the other branch having a discharge mouth at the bottom of said body, and valve 60 means for selectively directing the air to be discharged either at the rear or at the bottom of the body. 65

4. An aeroplane comprising a body having its top and bottom walls converging into a horizontal front edge and being provided with a pilot's cabin upon said top wall, propellers at said front edge and engines for actuating the same, blower means including a blower fan and an engine for operating the same for withdrawing air from the front of the body and blowing it out either to the rear or at the bottom thereof, valve means for directing the discharge of said air, and control means in the pilot's cabin for readily controlling all of said valve means and also said blower engine. 70 75

5. An aeroplane comprising a flattened body having a horizontal front edge and propellers mounted at the front thereof, 80 tubular blower mechanism with a pair of intake mouths adjacent each propeller in said edge, fan means with an engine therefor and with outlet means and valve means for selectively directing the air either to the rear or to the bottom of said body, and control means for controlling the valve means and the fan engine to direct the air discharge and have said mechanism either co-operate with said propellers or to function independently 85 90 95 thereof.

In testimony whereof I have signed my name to this specification.

ELIAS A. KAUFFMAN.
